UNITED STATES PATENT OFFICE.

MICHAEL LIPTAK, OF ST. PAUL, MINNESOTA, ASSIGNOR TO A. P. GREEN FIRE BRICK COMPANY, OF MEXICO, MISSOURI, A CORPORATION OF MISSOURI.

FURNACE WALL.

Application filed April 24, 1922. Serial No. 556,195.

To all whom it may concern:

Be it known that I, MICHAEL LIPTAK, a citizen of the United States, residing at St. Paul, in the county of Ramsey and State of Minnesota, have invented certain new and useful Improvements in Furnace Walls; and I do hereby declare the following to be a full, clear, and exact description of the invention, such as will enable others skilled in the art to which it appertains to make and use the same.

My present invention relates to wall structures and is in the nature of a modification or refinement of the wall structure disclosed and claimed in my pending application Serial Number 550,841, filed of date April 8, 1922, and entitled "Furnace walls".

Generally stated, the invention consists of the novel construction, arrangement and combinations of parts hereinafter described and defined in the claims.

In the accompanying drawings, which illustrate the invention, like characters indicate like parts throughout the several views.

Referring to the drawings:

Fig. 1 is a perspective showing a portion of a wall embodying my invention, some of the blocks thereof being removed and some parts being broken away;

Fig. 2 is a fragmentary plan view of the wall shown in Fig. 1, the buckstays being in horizontal section;

Fig. 3 is a vertical section taken on the line 3—3 of Fig. 2;

Fig. 4 is a plan view showing one of the sill blocks of the wall and showing also one of the anchor rods;

Fig. 5 is a perspective showing one of the sill blocks;

Fig. 6 is a perspective showing one of the shelf-forming blocks;

Fig. 7 is a fragmentary perspective showing several of the pilasters and superimposed lintels;

Fig. 8 is a perspective of one of the lintels, showing the same turned upside down;

Fig. 9 is a view corresponding to Fig. 3, but illustrating a slightly modified construction and the buckstays being omitted;

Fig. 10 is a perspective showing one of the sill blocks of the structure illustrated in Fig. 9;

Fig. 11 is a perspective showing one of

the shelf-forming blocks of the structure illustrated in Fig. 9;

Fig. 12 is a view corresponding to Fig. 9 but illustrating a still further slightly modified form of the wall;

Fig. 13 is a view corresponding to Fig. 9 and illustrating a still further modified construction of the wall;

Fig. 14 is a perspective showing one of the sill blocks illustrated in Fig. 13;

Fig. 15 is a perspective showing one of the shelf-forming blocks illustrated in Fig. 13;

Fig. 16 is a perspective showing one of the metallic anchors illustrated in Fig. 13;

Fig. 17 is a view corresponding to Fig. 13 but illustrating a still further modified construction;

Fig. 18 is a perspective view of one of the sill blocks shown in Fig. 17;

Fig. 19 is a perspective of one of the shelf-forming blocks shown in Fig. 17;

Fig. 20 is a perspective showing an anchor block used in connection with the sill blocks and shelf-forming blocks of the construction illustrated in Fig. 17;

Fig. 21 is a view corresponding to Fig. 17 but illustrating a still further slightly modified construction;

Fig. 22 is a perspective of one of the sill blocks shown in Fig. 21; and

Fig. 23 is a perspective of one of the shelf-forming blocks shown in Fig. 21, said block being turned upside down.

This improved wall, as in the wall of my above identified pending application, the complete wall structure, when designed as an outside wall, is made up of what may be designated as a permanent masonry outer wall and a replaceable high refractory masonry inner wall. In the preferred construction, the permanent outer wall is preferably faced with fire brick or bricks, which become a relatively permanent part of said outer wall.

Attention is first called to the construction illustrated in Figs. 1 to 8, inclusive, wherein the outer common brick 24 of the permanent outer wall may be laid in any desired number of horizontal layers and is faced with fire brick 25. Sill-forming blocks 26 are built into the permanent outer wall and preferably extend completely through the

same. For an important reason, which will presently appear, these sill-forming blocks 26, at their vertical edges, are tapered inward. Between the sill-forming blocks 26, 5 said outer wall is formed with short pilasters, preferably made up of several fire bricks 27 placed one on top of the other. The bricks 27 that form these pilasters, at their vertical edges, are tapered toward the 10 outer surface of the permanent wall and fit against the tapered edges of the sill blocks 26, so that the latter are limited in their inward movement, that is, are positively prevented from being removed by inward movement 15 but are capable of being moved by outward movement. The pilasters are capped by lintels 28 in the form of large fire tiles or blocks seated on said columns and forming a horizontal layer, which preferably 20 does not extend back through the common brick masonry of the said permanent outer wall. The cooperating sill blocks, pilasters and lintels form, in the inner face of the permanent outer wall, vertically spaced horizontal 25 rows of rectangular pockets that extend back into but not through the common brick masonry 24. In the construction here illustrated, the sill-forming blocks 26, at the bottoms of the pockets, are formed 30 with raised beads 29, preferably curved in cross-section and located considerably inward of the inner ends of said sill blocks. The replaceable inner wall should be made 35 up entirely of high refractory bricks or tiles and, as shown, is made up chiefly of horizontal belts of fire bricks 30, but between these belts are interposed horizontal layers of shelf-forming blocks or tiles 31 that preferably have the same horizontal width as 40 the inner edge portions of the pockets of the permanent wall structure and, hence, are adapted to fit into said pockets and to be seated on the sill blocks 26. These shelf-forming tiles 31 are preferably long enough 45 to extend through the replaceable inner wall and to the backs of the pockets in the permanent outer wall. To cause them to interlock with the sill blocks, said blocks 31 are formed on their under-surfaces with trans- 50 verse lock grooves 31^a of the same cross-section as the beads 29, so that they are adapted to fit the latter. Key blocks 32, preferably in the form of tapered fire bricks, arranged in groups, are placed on top of the shelf-forming blocks 31 and forced into the 55 pockets and against the beveled under-surfaces 28^a of the lintels 28 and, when thus applied, rigidly hold the shelf-forming blocks in horizontal positions interlocked to the 60 permanent outer wall.

Spaces in the replaceable inner wall, between the shelf-forming blocks 31, are filled in by supplemental shelf-forming tiles or blocks 33 that extend only through said replaceable inner wall and abut against the

pilasters 27. It will now be observed that the fire brick masonry belts 30 are built on the shelf-forming tiles 31 and 33 and are supported by the said tiles 31 and completely fill the spaces between the horizontal rows 70 of vertically spaced shelf-forming blocks.

Certain of the sill blocks 26 are arranged in vertical rows that align with buckstays 35, which latter, as shown, are made up of upright steel channel beams placed back to 75 back but slightly spaced, in the customary or any suitable way; and for anchoring these sill blocks directly to said buckstays, I preferably provide anchor rods 36 provided at their outer threaded ends with nuts 37 and 80 washers 38 and, at their inner ends, with downturned hook lugs 39. The sill blocks that are aligned with the buckstays are formed in their upper surfaces with grooves 40 that terminate in depressed lock notches 85 or pockets 41. When the rods 36 are turned, as shown in Fig. 4, they may be inserted endwise through the grooves 40 and then their lugs 39 can be turned downward into interlocking engagement with the notches 90 41. Then, when the nuts 37 are tightened, the sill blocks will be directly anchored to the buckstays and the furnace will be indirectly anchored to said buckstays.

When the shelf-forming blocks 31 are interlocked to the sill blocks, the latter will be positively interlocked in the wall so that they cannot possibly be removed by outward movement or otherwise. When the shelf-forming blocks are removed from position, 95 then it will be possible to remove the sill blocks by endwise movement in a direction toward the outer face of the wall, but this should require the immediately overlying bricks of the permanent outer 100 wall first to be removed. This makes possible the replacement of the sill blocks, if at any time they should become damaged. The tapered form above described is a convenient form for preventing the sill blocks 110 from being moved inward and for keeping the same interlocked in the permanent wall, except by the manipulations above noted.

Fig. 1 illustrates very clearly the fact that any one or more of the bricks or blocks of the replaceable inner wall may be removed and replaced at will without disturbing certain other bricks or blocks that have not been damaged. The removal of the shelf-forming blocks requires only that the overlying bricks be removed therefrom and that the key blocks 32 then be removed.

The sill-forming blocks and the fire bricks 27 that form the pilasters will very seldom require replacement, while the shelf-forming 125 blocks 31 may very frequently require replacement. Hence, the said shelf-forming blocks will be shipped in much larger quantities than the sill-forming blocks and the ability to compactly pile the same together 130

for shipment is, therefore, a very important matter. With the arrangement described and with other arrangements hereinafter illustrated, the said shelf forming blocks are formed with six flat surfaces without projections, but, in some instances, with indentations, and as they are rectangular in form, they may be piled together as closely as ordinary bricks or other perfectly rectangular blocks and this reduces the cost of shipment and the liability of breakage of the blocks.

The construction illustrated in Figs. 9, 10 and 11 is like that illustrated in the views above described, with the following exceptions, to wit: the sill-forming blocks 26^a are formed on their upper faces with approximately semi-cylindrical bosses or perforations 42 that are engageable with reversely formed indentations 43 in the shelf-forming blocks 31^a. Also, the lintels 28^a are not beveled at their under-surfaces and the key blocks 32^a are not tapered but are of the ordinary brick form.

25 The construction illustrated in Fig. 12 is like that illustrated in Figs. 1 to 7, inclusive, except that the permanent outer wall and replaceable inner wall are spaced to form an air gap 44 and the sill blocks 26^b and the shelf-forming blocks 31^b have flat engaging surfaces.

The construction illustrated in Fig. 13 is like that illustrated in Fig. 12, except that the two walls are built close together, or without air space between them, and that the sill blocks 26^c and shelf-forming blocks 31^c are interlocked by metallic anchors 45. These metallic anchors 45 have downturned lugs 46 and upturned lugs 47. The sill blocks 26^c are formed with channels 48 that terminate in depressed extremities that receive the anchors 45 and their depending lugs 46, while the shelf-forming blocks 31^c are formed with pockets 49 that receive the upturned lugs 47 of said metallic anchors.

The construction illustrated in Figs. 17, 18, 19 and 20 is like that illustrated in Fig. 13, except that the sill-forming blocks 26^d and shelf-forming blocks 31^d are formed, respectively, with rectangular pockets 50 that receive an anchoring brick or block 51, which positively interlocks the two blocks 26^d and 31^d together.

The construction illustrated in Figs. 21, 55 22 and 23 is like that illustrated in Fig. 13, except that the sill blocks 26^e and shelf-forming blocks 31^e, in addition to being interlocked by the metallic anchor 45, are further interlocked by ledges 52 and 53 formed, 60 respectively, on said blocks.

What I claim is:

1. A composite furnace wall comprising a permanent masonry outer wall having therein horizontal rows of sill-forming blocks, 65 overlying horizontal rows of lintels and in- tervening pilasters, forming vertically spaced rows of horizontally spaced pockets, in combination with a high refractory replaceable masonry inner wall including shelf-forming blocks projected into and anchored within the pockets of said permanent wall, said shelf-forming blocks each being substantially the width of a co-operating pocket. 70

2. The construction defined in claim 1 in further combination with key blocks filling the space between the tops of said shelf-forming blocks and the tops of said pockets and anchoring said shelf-forming blocks within said pockets. 80

3. A composite furnace wall comprising a permanent masonry outer wall having therein horizontal rows of sill-forming blocks, overlying horizontal rows of lintels and intervening pilasters, forming vertically spaced rows of horizontally spaced pockets, in combination with a high refractory replaceable masonry inner wall including shelf-forming blocks projected into and anchored within the pockets of said permanent wall, the said shelf-forming blocks being horizontally spaced and said pilasters being extended downward between the same. 90

4. A composite furnace wall comprising a permanent masonry outer wall having therein horizontal rows of sill-forming blocks, overlying horizontal rows of lintels and intervening pilasters, forming vertically spaced rows of horizontally spaced pockets, in combination with a high refractory replaceable masonry inner wall including shelf-forming blocks projected into and anchored within the pockets of said permanent wall, said shelf-forming blocks each being substantially the width of a co-operating pocket, 100 the said shelf-forming blocks being horizontally spaced and said pilasters being extended downward between the same. 105

5. The structure defined in claim 2 in which said sills and shelf-forming blocks have co-operating lock surfaces that are held interlocked by said key blocks. 110

6. The structure defined in claim 2 in further combination with filling blocks, each of which fills a space between the projecting portions of two adjacent shelf-forming blocks. 115

7. The structure defined in claim 2 in which said key blocks are wedge-shaped and the under surface of the overlying lintels are correspondingly beveled. 120

8. A composite furnace wall comprising a permanent masonry outer wall having therein horizontal rows of sill-forming blocks, overlying horizontal rows of lintels and intervening pilasters forming vertically spaced rows of horizontally spaced pockets, the said sill-forming blocks being wider at their outer than at their inner ends, where- by they are made removable by outward 130

movement only, in combination with a high refractory replaceable masonry inner wall including shelf-forming blocks projecting into the pockets of said permanent outer wall.

9. The structure defined in claim 8 in which co-operating sill-forming and shelf-forming blocks are locked together, said shelf-forming blocks positively holding the 10 sill-forming blocks against outward movements while the former are in position.

10. The structure defined in claim 9 in further combination with buckstays and

with metallic anchors directly anchoring certain of said sill-forming blocks to said 15 buckstays.

11. The structure defined in claim 1 in which said sill-forming blocks have an inward taper limiting their inward movement but permitting removal by outward 20 movement.

12. The structure defined in claim 11 in which said pilasters in horizontal section flare inwardly.

In testimony whereof I affix my signature.
MICHAEL LIPTAK.
